[57] CLAIM

The ornamental design for a support for an archer's compound bow, as shown.

DESCRIPTION

FIG. 1 is a perspective view of a support for an archer's compound bow shown as used in accordance with the invention;

FIG. 2 is a front elevational view of the support shown in FIG. 1;

FIG. 3 is a rear elevational view, with straps removed, of the support shown in FIG. 2;

FIG. 4 is a side elevational view of the support shown in FIG. 2, the opposite side of which is a mirror image not shown;

FIG. 5 is a top plan view, with straps removed, of the support shown in FIG. 2;

FIG. 6 is a bottom plan view, with straps removed, of the support shown in FIG. 2; and,

FIG. 7 is a rear view of the support shown in FIG. 1.
